UNITED STATES PATENT OFFICE.

EMILE RIMAILHO, OF PARIS, FRANCE, ASSIGNOR TO COMPAGNIE DES FORGES ET ACIERIES DE LA MARINE ET D'HOMECOURT, OF PARIS, FRANCE.

WHEELED GUN-CARRIAGE WITH WIDE SCOPE OF FIRE.

1,272,106.

Specification of Letters Patent.

Patented July 9, 1918.

Application filed June 17, 1914. Serial No. 345,578.

To all whom it may concern:

Be it known that I, EMILE RIMAILHO, a citizen of the French Republic, and residing in Paris, France, 98 Rue de la Victoire, consulting engineer, have invented certain new and useful improvements in and relating to Wheeled Gun-Carriages with Wide Scope of Fire, of which the following is a complete specification.

10 In those gun carriages which at the moment of firing are in contact with the ground at four points, the latter points are represented on the one hand by the lower part of each of the wheels, (hereinafter called the "axle wheel" system) and on the other hand by the ends of two trails (hereinafter called the "trail" system), special arrangement having to be made in order to enable all the four points of support to 20 grip the ground during the firing.

The object of the present invention is the construction of a gun carriage in which the above purposes are secured, by connecting the "axle-wheel" system to the "trail" system through the agency of a spherical or ball joint, the male part of which is carried by one of the two systems and the female part by the other; the carriage proper, carrying the pivot which supports the gun 30 can form part either of the "axle-wheel" system or of the "trail" system.

On the drawings annexed:

Figure 1 is a plan with a part section of a first working construction,

35 Fig. 2 is an elevation with part section, Fig. 3 is a section through A—B of Fig. 2,

Fig. 4 is a section through C—D of Fig. 2,

Figs. 5 to 7 are similar views of another working construction,

40 Figs. 8 and 9 are respectively a plan with section and cross section of a variant,

Figs. 10 and 11 are details,

Figs. 12 to 18 show another working construction, in which

45 Fig. 12 is an axial longitudinal section on the line G—G of Fig. 16.

Fig. 13 is a vertical section on the line H—H of Fig. 12.

Fig. 14 is a vertical section on the line

50 I—I of Fig. 12.

Fig. 15 is a vertical section on the line

J—J of Fig. 12.

Fig. 16 is a plan with part section on the line E—E of Fig. 12.

Fig. 17 is a horizontal section on the line 55 F—F of Fig. 12.

Fig. 18 is a view similar to Fig. 16 showing the trails and the small carriage in another position relatively to the axle.

Fig. 1 shows by way of example, a working construction in which the male part 1 of the ball joint, is carried by the trail system, the female part 2 being carried by the "axle-wheel;" Fig. 2 shows in this case the body 3 of a gun carriage fixed to the 65 system "axle-wheel" by means of the axle 4 and carrying the recess 5 for receiving the pivot supporting the gun.

Fig. 5 shows by way of example a form of construction in which the male part 1 of the ball joint is carried by the "axle-wheel" system, and the female part 2 is carried by the "trail" system. Figs. 6 and 7 in this case show a gun carriage body 3 fixed in the "trail" system and carrying the recess 75 5 for the gun pivot.

Figs. 1 to 7 likewise show the connections which allow all the relative movements which the two systems are required to be able to carry out, in relation to each other. 80 The ball joint allows the "trail" system (Fig. 1) to pass from position 6, 7 to position 6', 7', the line 8 of the point of support of the butt ends being parallel to the axle when the axis of the "trail" system is 85 perpendicular to the axis, but being able to take up the position 8' and 8'', oblique relatively to the axle, according to the requirements of the ground.

Fig. 4 shows that the ball joint also allows 90 the "trail" system 6, 7 to be inclined relatively to the axle from right to left or from left to right as required by the ground while the axle remains horizontal.

Finally if we consider the movement of 95 elevation which the "trail" system must be capable of undergoing around the axle journal when the butt ends are raised, for instance, it may be desirable to include the whole of the carriage in this movement; 100 with this object, for the working constructions of Figs. 1 to 4, a sliding piece 9 is able to undergo lateral displacement in the wide window 10 contained between the sup-

ports 2^a and 3^a of the gun carriage. This slide 9 has an axial hole, in which the cylindrical prolongation 11 of the front part of the trail system engages so that in all 5 positions which the "trail" system is able, owing to the ball joint, to assume right and left of that perpendicular to the axle, the movement allowing the system to incline to the right or to the left owing to the same 10 ball joint is equally possible.

In the working construction of Figs. 5, 6 and 7, the possibilities of inclining the system on either side of the perpendicular to the axle and making it lean right or left, are 15 provided by the cut away parts 12 in the cap 13 forming the socket into which the ball 1 fits; as regards the actuation or drive of the system around the axle, it is brought about by the permanent connection of the 20 trails and the gun carriage body (Fig. 6), a cylindrical pin 14 (Figs. 10 and 11) belonging to the carriage body projects into and is surrounded by an oscillating tube 15 which is provided to oscillate in a slot in 25 the axle for the purpose of constantly directing the axle journals in relation to the carriage trails.

The foregoing working constructions have shown a joint in which the ball was complete. Figs. 8 and 9 represent a variant which shows that it is possible to confine oneself to a part ball 21, the center of which may be placed either above or below the axle or else on the axle itself.

Evidently the ball and the socket joint can be replaced by a Cardan joint, and the effects described above thus obtained.

In the above described constructional forms, and more particularly in those illustrated on Figs. 1 to 4, the ball of the joint between the "trail" system and the "axle-wheel" system is arranged below the axle and in front of it, the small carriage which supports the gun being pivoted in a lodgment fixedly connected with the axle tube.

In the working construction of Figs. 12 to 18, the center of the ball of the joint is brought back on the axis of the axle, which results in rendering the whole lighter and 50 simpler in construction, as the pivot of the small carriage may then be arranged on the "trail" system itself so as to offer direct resistance to the strain of firing without passing through the agency of the axle tube or 55 axle.

In this constructional form, the horse-shoe part 41 of the "trail" system ends in a ball 42 lodged in a recess of the same shape 43 provided in the axle 44, in which recess it 60 is held by means of two threaded half collars 45 (Figs. 12 and 14).

In this horse-shoe shaped part 41 there is provided a bearing recess 46 of a rectangular cross section, intended to receive a socket 65 47 which can oscillate about gudgeons 48

and in which the pivot 49 of the small carriage 50 is mounted. The bearing recess 46 is suitably bell-mounted in its upper part and its lower part to allow of the pivoting of the "trail" system about the horizontal 70 axis.

The spherical part of the axle carries on its upper face a cylindrical vertical pin 51, the axis of which passes through the center of the ball and which serves as a pivot for 75 a plate 52 belonging to the socket 48 of gudgeon 47. This plate carries a toothed segment 53 on which the pinion 54 for direction pointing runs. That is, when carriage 50 is operated by pinion 54 it is merely 80 for the purpose of training, and the pinion 54 may control any displacement of carriage 50 independently of the trail, pinion 54 being controlled by a worm wheel as indicated in Fig. 12. The plate is held in a suitable 85 position relatively to the axle by means of a triple clamping arrangement 55-56-57 (Figs. 12, 15, and 16) concentric with the cylindrical pin. The bottom of the plate 52 carries on the back a cylindrical part 58 90 (Fig. 13) concentric with the axis of the gudgeons 48, by means of which part the plate is supported on the cross bar 41 of the horse-shoe. A washer 59 (Figs. 12 and 13) likewise having a cylindrical surface, is interposed between the lower part of this cross bar 41 and the head of the screw 60 which 95 fixes the pivot 49.

The neck 61 of the ball rests on the axle by means of a two part collar 62 (Figs. 12 100 and 14) of circular internal section and polygonal external section, so as to provide a suitable bearing surface for all the positions of transverse inclination.

It will be remarked that in this construction (Figs. 12 to 17), the pivot 49 of the small carriage is mounted on the "trail" system itself, which enables the trails to support directly the strain of firing, while admitting of the transverse pivoting and lateral displacement of the "trail" system. The gudgeons 48 by no means form an axis of oscillation for the trails, but an agency insuring constant connection between the small gun carriage and these trails, irrespectively of the transverse direction of the latter with reference to the axle.

When the two "trails" are laterally displaced, they cause to pivot about the cylindrical pin 51 the plate 52 and the whole 120 of the small carriage 50 and the gun itself relatively to the wheel-axle system, this group as a whole being displaced in a plane parallel to the axle.

It will be seen furthermore that when 125 the rear ends are raised the movement of elevation undergone by the "trail" system around the axle journals carries the entire gun carriage along with it.

The arrangement described of a spherical 130

recess 43 provided in the center of the axle 5 enables the wheel brake control to be lodged here so as to reduce the space occupied by the carriage as a whole, and preventing the dust making its way into this brake.

This control comprises a box 63 (Figs. 12 and 17) mounted in an invariable position in a tube end 64 of the recess 43. This box carries at its outside end a hand wheel 65 fixedly connected with a screw 66 mounted so as to be able to turn without longitudinal displacement. This screw is in engagement with a nut 67 sliding in the box 63 and supporting a plate 68 on which is pivoted a pulley 69. A cable 70, the middle of which catches on this pulley, passes elsewhere onto two fixed guide pulleys 71 mounted in the recess 43, and its ends pass through the interior of the axle 44 and run out to the usual 20 wheelbrake control levers, not shown, consisting of spring segments.

What I claim is:—

1. A wheeled gun carriage comprising an axle wheel frame, a trail frame united thereto by a ball and socket coupling, braking means carried by the wheels of the carriage, and means carried by the ball and socket coupling for controlling the braking means.
2. A wheeled gun carriage comprising an axle wheel frame, and a trail frame coupled thereto by a ball and socket joint, the ball disposed in the front of the trail frame and the socket disposed in the axle, said 35 trail frame also provided with a pivotally mounted oscillatory small gun carriage.
3. A wheeled gun carriage comprising an axle wheel frame and a trail frame coupled thereto by a ball and socket joint, said 40 joint consisting of a ball and neck thereon

Copies of this patent may be obtained for five cents each, by addressing the "Commissioner of Patents, Washington, D. C."

held in a recess formed therein, a pair of threaded half collars, the neck resting on the axle and extending through a two part socket, the internal section of which is cylindrical and the external section being polygonal whereby a constant surface of support is obtained irrespective of the direction of the trails relatively to the axle. 45

4. In a wheeled gun carriage comprising an axle wheel frame and a trail frame coupled thereto by a ball and socket connecting a cylindrical socket having oppositely disposed gudgeons, said socket secured to a plate pivotally mounted on a vertical pin reaching from the upper portion of the axle, the axis of said pin passing through the center of the trail joint ball, said plate held to the axle by clamps concentric to the vertical pin, a tooth segment supported by said plate, direction pointing pinion meshing with said segment, said plate having a cylindrical surface in its lower rear portion concentric with the gudgeons. 50

5. A wheeled gun carriage comprising in combination an axle wheel frame and a trail frame coupled thereto by a ball and socket connection, a movable pulley and fixed pulleys therein, a brake operating cable threaded around said pulleys within the ball member of the socket, openings in the 55 sides of the ball and the socket through which the ends of the cable may pass. 60

In testimony whereof I have hereunto set my hand at Paris (France), this fifth day of June, 1914.

EMILE RIMAILHO.
